CURRENT-LIMITING FUSIBLE PROTECTIVE DEVICE

William S. Edsall, Boston, Mass., and Kenneth W. Swain, Hampton, N. H., assignors to The Chase-Shawmut Company, Newburyport, Mass., a corporation of Massachusetts

Application October 23, 1951, Serial No. 252,676

25 Claims. (Cl. 200—120)

1

This invention relates to improvements in current-limiting fusible protective devices, i. e., interrupting devices which operate so rapidly that the maximum current which can occur in case of overloads in the nature of a short-circuit is limited to values substantially less than the available short-circuit current of the circuit or system. Such devices, if used in an A. C. circuit, effect interruption thereof in case of high overcurrents in less than half a cycle of the current wave. The invention refers more particularly to current-limiting protective devices of the present kind wherein plural and multiple individual current-limiting units may be variously combined within a surrounding protective medium to attain superior current-limiting characteristics and results which are predeterminable by proper selection of the kind, the number and the manner of association of the individual units.

This application is a continuation of now abandoned application Serial No. 60,328, filed November 16, 1948.

It is among the objects of the invention to provide current-limiting electrical protective devices which more effectively can accomplish current-limiting circuit interruption of circuits as compared with current-limiting devices heretofore available.

Another object is to provide current-limiting devices wherein individual current-limiting units of predetermined current-limiting characteristics are combined in parallel or in series in a plural or multiple unit device whose individual units are protectively surrounded by a dielectric medium within which the individual units operate and in the midst of which gaseous products may be vented from the individual units.

A further object is to provide current-limiting devices wherein individual current-limiting units are connected in parallel in order to produce a plurality of parallel unstable arcs, and more particularly to provide a current-limiting fuse wherein the number of parallel unstable arcs which are formed when the fuse blows exceeds the number of current-limiting units of which the fuse is made up.

Another object of the invention is to provide a fuse comprising a plurality of individual current-limiting units of which each has a fuse link varying in cross section along its length for causing gradual or progressive insertion of arc resistance into the circuit in order to limit voltage surges incident upon too rapid interruption.

Another object of the invention is to provide a fuse comprising a plurality of individual current-limiting units of which each has a fuse

link adapted to form sequentially a plurality of points of break for causing gradual or progressive insertion of arc resistance into the circuit.

Still another object is to provide current-limiting devices wherein a plurality or multiplicity of fusible elements are individually encased to constitute individual current-limiting units, and wherein the individual units are combined in parallel or in series within an enclosure which, or means within which, forms a dielectric barrier between the opposite terminals of each unit and between the terminals of units which are in spaced relation to each other.

Yet another object is to provide current-limiting devices wherein a plurality or a multiplicity of individual tubular units have fusible elements separately enclosed within the respective units with each fusible element surrounded by a filler material within its unit-enclosure, all of the said fusible elements being electrically connected together in parallel or in series, or some in parallel and others in series, and each tubular unit being closely surrounded by dielectric material which resists interior pressures tending to rupture individual units.

Another object is to provide a plural-unit or a multiple-unit current-limiting device wherein each unit comprises an insulating tube and a strip or link of fusible conducting material enclosed in the tube and surrounded by a pulverulent arc extinguishing filler, the strip having a series of fusing regions therealong, and the tube having restricted passages for venting of high pressure gases from the tube into granular or pulverulent dielectric material which closely surrounds the individual units.

A still further object is to provide a current-limiting device wherein separately encased current-limiting units are electrically connected in parallel within a mass of dielectric material and wherein in response to short-circuit or the like currents, interruption is sequentially initiated within the units.

It is, moreover, an object and purpose of the invention generally to improve the structure, operating characteristics, and over-all effectiveness and efficiency of current-limiting devices wherein individual current-limiting units of predetermined characteristics are combined to produce devices of desired plural-unit and multiple-unit interrupting capacities.

In the accompanying drawings:

Fig. 1 is a plan view of a multiple-unit current-limiting electrical protective device embodying features of the invention; a portion of the

outer casing being broken away, and the outermost unit being partly in medial cross-section;

Fig. 2 is a cross-sectional view on line 2-2 of Fig. 1;

Fig. 3 is a medial cross-sectional view of a modified form of multiple-unit device, the cross-section being approximately on line 3-3 of Fig. 4;

Fig. 4 is an end elevation of the device of Fig. 3, with a portion of the end wall broken away;

Fig. 5 is a medial cross-sectional view of another modified form having two units connected in series, the cross-section being approximately on line 5-5 of Fig. 6, but the units being shown in elevation;

Fig. 6 is a cross-sectional view on line 6-6 of Fig. 5;

Fig. 7 is a medial longitudinal cross-sectional view of one of the units of Figs. 1 and 2, on a larger scale;

Fig. 8 is a medial longitudinal cross-sectional view of a current-limiting device having three individual units in tandem-series relation within a capped outer tube, the individual units being in elevation;

Fig. 9 is a side elevation of a multiple-unit device comparable to that of Figs. 1 and 2 but having generally rectangular shape and having individual units of a modified form; and

Fig. 10 is a diagrammatic showing of current-limiting units having two pairs of series connected units connected in parallel.

Referring to the drawings, the current-limiting devices of Figs. 1-4 and 9 are representative of multiple-unit devices in which any desired number of individual current-limiting units may be associated together in parallel to provide an assembly having current-limiting capacity and characteristics predetermined as essential or desirable for any particular circuit.

In the device of Figs. 1 and 2, thirty-four individual units 10 are mounted in spaced parallelism between the metallic terminal members 12, 14, each unit 10, in and of itself, being a complete current-limiting device of predetermined current carrying and interrupting capacity. Each unit 10 might be used alone for service in accordance with its rating. If the number of units 10 is multiplied, as needed, and if the units are electrically connected in parallel, a composite current-limiting device of any desired total current carrying and interrupting capacity may be produced.

Each unit 10, as embodied in the multiple unit device of Figs. 1 and 2, has a tubular insulating casing 16, of any suitable material, capped at its opposite ends by the metallic end caps 18, 20. However, as seen in the larger scale unit 10 of Fig. 7, the end caps 18, 20 are initially applied to a casing 16 by merely placing them over the casing ends, with a snug but not tight fit of the cap flanges around the casing walls. In a plural-unit or multiple-unit device, the relatively loosely applied caps become secured on the casings 16 during the assembly procedure, as later will appear. It should be understood, however, that the caps may be crimped or be otherwise secured on the unit casings.

The casing 16 of a unit 10 may be made of any suitable material capable of withstanding extreme heat and pressure, such as porcelain and known special composition materials but, in the devices of the invention, circuit interruption is effected in a manner which reduces substantially the amount of heat and pressure to

which individual units are subjected, as compared with prior comparable units, making it practicable and safe to employ relatively inexpensive unit casings 16. Actually, casings of vulcanized fibre of the varieties conventionally used for cartridge fuse casings have proven entirely adequate.

Each unit 10 has a fusible strip or link 28 extending within its casing 16, with its opposite ends electrically connected to the opposite end caps 18, 20 as by high melting temperature solder, or the like. The strips 28 may be of any suitable fusible conducting material, such as silver or zinc, or the end portions may be of one material with a central portion of a lower melting temperature material. For example, in Fig. 7, the end portions 28' may be of silver and the central portion 28'' of zinc. Each fusible strip 28 has a series of holes 30 therein, each hole leaving a pair of intact necks 32 of reduced cross-section. The holes 30 are spaced apart enough to leave substantial portions of the strip material intervening between the respective pairs of reduced necks 32, these intervening portions being adapted, in large part, to remain unfused when fusing at the reduced necks 32 occurs. The provision of two separate current paths at the point of each hole results in the formation of two separate arclets at each pair of reduced necks 32 when the link is subjected to a short-circuit or the like current. This promotes rapid sequential extinction of the arclets, since arcs in parallel are unstable, as is well known in the art. The number of pairs of reduced necks 32, with the required spacing, will be predetermined in accordance with the desired or contemplated voltage rating of any individual unit, and then the number of the units required to be associated together will be selected in accordance with

40 the particular current rating desired to be given to the composite structure. Inasmuch as each arclet in any particular unit will provide an arc reignition voltage in the order of several hundred volts, the number of holes in the fusible strips 28 preferably will be selected to provide a total or cumulative arc voltage in any particular device at least equal to the circuit voltage plus the estimate inductive voltage of the circuit to be protected, so that there will be equilibrium between the sum of the arc voltages at all points of break and the sum of the circuit and inductive voltage.

An arc extinguishing filler material surrounds the fusible strip or link 28 in each unit 10 throughout the extent of the strip in the casing, but the filler material 34 at the opposite end portions of the casing, as best seen in Fig. 7, is different from the filler material 36 at the central region. Inert granular quartz is preferred for the material 34 in the opposite end portions of the casing because of its high heat-absorbing and heat-conducting qualities.

The material 36 in the central region of the casing preferably will be a thermally insulating material such as gypsum, for example, while the arc extinguishing filler on the axially outer ends of the casing is a good conductor of heat as, for instance, quartz sand. When a current of short-circuit magnitude causes the fuse to blow, two fulgurites are formed at the axially outer ends of each casing. These fulgurites are separated by a gypsum zone in the center portion of the fuse. The use of a thermally poor conductor in 65 the center portions of the fuse units as filling

material tends to prevent excessive heating or charring of the center portions of the casings. Since there is an impediment against the flow of heat generated at the axially inner portions of the fuse units in radial direction, the heat there generated will tend to flow toward the axially outer ends of the fuse units, where it can be most readily dissipated. In fuse units according to the present invention layers of fulgurite-forming arc quenching material alternate with a layer of non-fulgurite-forming arc quenching material, i. e., gypsum. It has been found that multi-layer fillers of this kind reduce the tendency of current-limiting fuses to permit follow-currents to persist, i. e., small currents to flow through the fuse for an appreciable time after interruption of the circuit has been substantially achieved. The persistence of follow-currents is due to the fact that fulgurites are moderately good conductors of electricity before they are cooled down below a certain temperature. If, however, a fulgurite is sub-divided into two or more portions by a gap formed by a non-fulgurite-forming arc quenching material, as, for instance, gypsum, which has a smaller conductivity at elevated temperature than quartz sand, then the tendency for the flow of follow currents is much reduced. Subdivision of fulgurites by substances having a lesser tendency at elevated temperatures to permit the passage of current than quartz is particularly desirable where the fuses are intended to interrupt D. C. circuits. To fill a casing entirely with a material as gypsum is not indicated since it has but limited heat-dissipating ability and tends to evolve large amounts of gas under the heat of the arc which, in turn, tend to create sufficiently high pressures to break the casings.

Suitable disks 37, slotted to fit over the fusible element, may be inserted at the time of filling of the units, to maintain segregation of the different filler materials.

According to the invention, a plurality or a multiplicity of current-limiting individual units 10 are associated together to provide plural-unit and multiple-unit devices having desired current-limiting capacities and characteristics. In the Figs. 1 and 2 embodiment, the thirty-four units 10 are clamped endwise between the terminal members 12, 14, within an outer insulating tubular casing 38 which is secured to the terminal members, as by the screws 39. Quartz sand 40, or a comparable filler material, surrounds the units 10 within the outer casing 38, effectively insulating the units against flash over between terminals of individual units and between terminals of adjacent units. Also, if any particular unit 10 should become ruptured, the rupture will occur in the midst of the filler material 40 without any harmful effects on adjacent units and without materially affecting the circuit interrupting and current-limiting ability of the plural-unit or multiple-unit device as a whole.

A feature of importance resides in the provision for restricted venting of individual units 10 into the midst of the insulating filler material 40 where arc products escaping from units 10 are cooled and deionized in a most effective way and thus precluded from causing flash overs or doing harm of any other kind. As herein represented, each unit 10 has its end caps 18, 20 initially merely pressed over the ends of the unit casing 16 without any crimping of the caps on the casing. However, each of the terminal members 75

12, 14 includes a circular body part 12', 14' whose opposed faces have slightly tapering sockets 42, in each of which one of the unit end caps 18 or 20 is seated during assembly. After a desired number of units 10 have been arranged between the terminal parts 12', 14', these parts are forced toward each other under considerable pressure, forcing the unit end caps deeper into the respective sockets 42 and simultaneously deforming the cap flanges into clamping engagement with the end portions of the unit casing 16. This clamps the units 10 under endwise compression between the terminal bodies 12', 14' and positively secures the end caps on the casings. But the ends of the unit casing do not become sealed. Rather, minute passages are left between the casing walls and the caps through which hot gases can escape from the interiors of the units 10, in case that the pressure within the units exceeds a predetermined value. In other words, units 10 are but semi-sealed which permits pressure to be built up within units 10 up to a predetermined pressure level. Building up of pressure results in an increase of the dielectric strength of the gas within units 10, thus aiding interruption of the circuit. When the pressure reaches a dangerous level close to the point where the individual fuse casings might burst, the semi-seals of the fuse units operate in safety valve like fashion. Venting of the arc products and of gases evolved from filler material within the fuse units is harmless since the gases are vented into the insulating filler material 40 which surrounds the units.

Under particular conditions, especially where only a few units 10 are associated together, filler material may be omitted exteriorly of the units, in which case arc products venting from the unit casings may discharge into air or other gas enclosed within the outer casing 38.

Figs. 3 and 4 illustrate an embodiment of the invention generally similar to the Figs. 1 and 2 form, but having a solid body 44 of dielectric material surrounding the units 10, between the terminal bodies 12', 14'. The material 44 may be introduced as a liquid through an opening 45 in the outer casing 38' after the device has been assembled, solidifying within the outer casing, or a solid body of material 44 may be preliminarily formed with holes 46 for snugly receiving the unit casings prior to the capping thereof, the solid body, in the latter case, being clamped between the terminal bodies 12', 14'; when the unit caps are being deformed as described in connection with Figs. 1 and 2. In each case, however, it will be apparent that the material 44 positively supports and restrains the unit casing 16 against rupture and in addition thereto isolates their cap terminals so as to preclude possibility of arc over or flash over.

Fig. 9 shows a multiple-unit device which is generally similar to the Figs. 1 and 2 device but having longer individual units 10', which may be of higher voltage rating, clamped between terminal bodies 12', 14' of rectangular shape. The units 10' are mounted in the same manner as the units 10 of the Figs. 1 and 2 form, but the outer insulating casing is made up of four separate plates 38' which are secured in place by the screws 39'. Quartz sand 40, or the like, may be poured into the outer casing, around the units 10', through an open side after three of the plates 38' have been secured in place, the fourth plate being secured following the filling operation.

While the devices of Figs. 1-4 and 9 all have multiple units electrically connected in parallel

to provide large current-carrying capacity, it is desirable in some cases to combine the units in serially related groups in order to be able to give higher voltage ratings to plural-unit and multiple-unit devices.

Figs. 5 and 6 illustrate a two-unit device whose two units 10 are connected in series between terminal bodies 48 and within the outer insulating casing 50. Each terminal body 48 may have a socket 52 for receiving a unit end cap, as previously described, and may have a larger recess 54 for receiving a block 56 of insulating material in which a socket 58 is formed, to receive a unit end cap. A small insulating tube 60 extends between the two insulating blocks 56, and a conductor 62 extends through the tube and has one end connected to the unit cap which is seated in one block 56, and has its other end connected to the unit cap which is seated in the other block 56. Filler material 64 preferably surrounds the units 10, as in the earlier described embodiments. It will be obvious that the device of Figs. 5 and 6 will have a voltage rating substantially equal to the sum of the voltage ratings of the individual units 10.

In the Figs. 1-4, 9 and 5 and 6 embodiments, the terminal members 12, 14, terminal parts or bodies 12', 14', 12'', 14'', 12^a, 14^a and 48 are shown as relatively massive terminals which have large capacity for absorption and extraction of heat from the interior units, and they are in good heat-receiving relation to the end caps of the interior units, whereby relatively large and rapid transfer of heat to the terminals occurs in response to any substantial heat generation within the interior units. This avoids unnecessary operations of the protective devices in response to moderate overload currents which are of a harmless nature, and rapidly removes heat from the interior units when fusing of the units occurs, thereby permitting use of fuse links of smaller cross-section, with smaller reduced cross-section portions, than otherwise would be feasible, and minimizing any tendency toward build up of dangerous temperatures and pressures within the individual units.

Fig. 8 shows a tandem series arrangement of units 10, comparable to the units 10 of Figs. 1-4 and 7, within an outer insulating tube 38' in each end of which an exteriorly threaded sleeve 38'' is fixed for reception of a metallic end cap 38'''. Three of the units 10 are shown clamped endwise between the end caps 38''', with arc extinguishing filler material 40 surrounding the units 10. Here again the device will have a voltage rating substantially equal to the sum of the voltage ratings of the individual units 10.

In special cases, it may be desirable to assemble multiple-unit devices with some of the units in parallel and others in series to attain both an increased voltage rating and an increased current-carrying and interrupting capacity for a device as well as required current-limiting characteristics. This may be achieved by combining the features of the Figs. 1 and 2 and Figs. 5 and 6 forms within a single outer enclosure. Fig. 10 diagrammatically illustrates such a series-parallel relation of units 10.

Devices embodying the disclosed features of the invention have proven exceptionally efficient in the performance of current-limiting protection against short-circuit and the like currents, both in A. C. and in D. C. circuits and in both low and relatively high voltage service. The invention makes it practicable to assemble current-limiting

units in parallel or series or some in parallel and some in series relation to produce composite devices of any of a wide variety of voltage and current ratings. Individual unit constructions may be varied to provide different unit characteristics. If desired, units of different current carrying and interrupting capacity may be connected in parallel. In a multiple-unit device embodying the present invention, progressive insertion of arc resistance into the circuit and consequent avoidance of voltage surges is due to the coaction of several causes. Small tolerances or differences of the cross-sectional areas at the various points of break are in part responsible for the fact that arc initiation at the various points of break occurs in rapid sequence rather than simultaneously. Another cause responsible for gradual insertion of arc resistance into the circuit resides in the fact that the cross-section of each link increases from each point of arc initiation in a direction longitudinally of the link. The cross-section at the points of minimum cross-section is evidently equal to the difference between the width of the link and the diameter of the hole times the thickness of the link, whereas the cross-section at the points of maximum cross-section is evidently equal to the width of the link times the thickness of the link. In composite current-limiting fuses according to the present invention, magnetic effects and particularly the skin effect cause a larger portion of the current to flow through some units than others, and therefore units having an equal rating fuse before and after others. This triggering off of certain units in advance of others tends to reduce the rate of change of current and therefore to limit the inductive surge voltage. When the fusible elements have portions of different melting temperatures as herein disclosed, the portions of lower melting temperature are converted into arcs before the portions of higher melting temperature fuse.

Also, the unit construction wherein a fusible strip or link has a series of holes providing pairs of fusible conducting necks with substantial bodies of metal between adjacent pairs of the necks, permits interruption of circuits in the shortest time compatible with prevention of voltage surges and, on account of this fact, such units volatilize less metal and generate less heat than prior comparable units.

The provision for venting of units into the midst of surrounding dielectric material relieves internal pressures of units while the said surrounding dielectric material, especially in its solid form of Figs. 3 and 4, resists internal unit pressures which otherwise might be capable of rupturing the unit casings. But, according to the invention, actual rupture of a unit casing, if it should occur, will be in the midst of insulating dielectric material where it can have no appreciable ill effect upon adjacent units or upon the over-all efficiency of the device.

It should be understood that the particular embodiments of the invention illustrated in the drawings are representative rather than limiting and it is intended that the patent shall cover such modifications as fall within the scope of the appended claims.

70 We claim as our invention:

1. A current-limiting device comprising a pair of electrically conducting terminal members, a plurality of electrically conducting fusible elements electrically connected together with at least one element electrically connected to one of

said terminal members and at least one other element electrically connected to the other of said terminal members, each said fusible element having at least two portions of reduced cross-section, and a portion of relatively much greater cross-section intervening between said portions of reduced cross-section and having length between adjacent reduced cross-section portions at least equal to the length of each reduced cross-section portion, said portions of reduced cross-section being adapted to fuse substantially simultaneously in response to a rapidly rising current which is to be limited, and said intervening portion of each fusible element providing a mass of fusible metal which, in substantial part, continues unfused by extension of the arcs at said reduced cross-section portions, a separate enclosure of insulating material for each of said fusible elements, arc quenching filler material surrounding each fusible element within its said enclosure, a common insulating housing for said plurality of fusible elements and the enclosures thereof, said housing extending between said terminal members and maintaining them in a predetermined spaced relationship, and dielectric material within said housing between said terminal members and surrounding each of said separate enclosures.

2. A current-limiting device comprising a pair of electrically conducting terminal members, a plurality of electrically conducting fusible elements electrically connected together with at least one element electrically connected to one of said terminal members and at least one other element electrically connected to the other of said terminal members, a separate enclosure of insulating material for each of said fusible elements, arc quenching filler material surrounding each fusible element within its said enclosure, a common insulating housing for said plurality of fusible elements and the enclosures thereof, said housing extending between said terminal members and maintaining them in a predetermined spaced relationship, dielectric granular material within said housing surrounding each of said separate enclosures throughout the extents thereof between the terminal members, and restricted passage means permitting gases under pressure to vent from said separate enclosures into contact with said dielectric granular material, each of said plurality of fusible elements having a plurality of portions of reduced cross-section spaced substantially equidistantly along substantially the entire length of said link and a plurality of portions of relatively larger cross-section intermediate said reduced cross-section portions, each said reduced cross-section portion having a sufficiently small cross-sectional area to initiate arcing at instantaneous currents far below the available short-circuit current of a circuit in which the device is to serve, and each said relatively larger cross-section portion having a length being a multiple of the length of said reduced cross-section portions.

3. A current-limiting device comprising a pair of electrically conducting terminal members, a plurality of individual current-limiting units arranged between said terminal members, each said unit having an insulating casing and an electrically conducting fusible element within the casing surrounded by arc quenching filler material, and the fusible elements of all of said units being electrically connected together with at least one fusible element electrically connected to one of the terminal members and at least one

other fusible element electrically connected to the other terminal member, each said fusible element having at least two portions of reduced cross-section, and a portion of relatively much greater cross-section intervening between said portions of reduced cross-section and having length between adjacent reduced cross-section portions at least equal to the length of each reduced cross-section portion, said portions of reduced cross-section being adapted to fuse substantially simultaneously in response to a rapidly rising current which is to be limited, and said intervening portion of each fusible element providing a mass of fusible metal which, in substantial part, continues unfused by extension of the arcs at said reduced cross-section portions, insulating means extending between the terminal members and constituting, with said terminal members, an enclosure around said individual units, and dielectric material within said enclosure surrounding said individual units and substantially filling all spaces within the enclosure not occupied by said individual units.

4. A current-limiting device comprising a pair of electrically conducting terminal members, insulating walls rigidly maintaining said terminal members in spaced relation, individual current-limiting units clamped endwise between said terminal members and thereby electrically connected in parallel between said terminal members and surrounded by said insulating walls, granular inorganic insulating material surrounding said individual units within said surrounding wall, each of said units comprising an insulating tube, an electrically conducting fusible element arranged therein and having one end electrically connected to one of said terminal members and the other end electrically connected to the other of said terminal members, and an arc quenching substance surrounding the fusible element and filling the tube, and restricted passage means for venting arc products under pressure formed within each tube into said granular inorganic insulating material, each said fusible element having a plurality of portions of reduced cross-section spaced substantially equidistantly along substantially the entire length of said link and a plurality of portions of relatively larger cross-section intermediate said reduced cross-section portions, each said reduced cross-section portion having a sufficiently small cross-sectional area to initiate arcing at instantaneous currents far below the available short-circuit current of a circuit in which the device is to serve, and each said relatively larger cross-section portion having a length being a multiple of the length of said reduced cross-section portions.

5. A current-limiting device comprising a pair of electrically conducting terminal members, each said terminal member having a face disposed in spaced general parallelism with a similar face of the other terminal member, a multiplicity of insulating tubes clamped endwise between said terminal members and disposed in spaced general parallelism between said terminal members, an electrically conducting fusible element within each tube having its opposite ends electrically connected to different ones of said terminal members, each said fusible element having a plurality of portions of reduced cross-section spaced substantially equidistantly along substantially the entire length of said link and a plurality of portions of relatively larger cross-section intermediate said reduced cross-section portions, each said reduced cross-section portion

having a sufficiently small cross-sectional area to initiate arcing at instantaneous currents far below the available short-circuit current of a circuit in which the device is to serve, and each said relatively larger cross-section portion having a length being a multiple of the length of said reduced cross-section portions, arc quenching filler material surrounding the fusible element within each said tube, insulating walls rigidly maintaining said faces of the terminal members in their said spaced relation and surrounding said multiplicity of tubes, granular dielectric material surrounding each of said tubes within said surrounding insulating walls, and restricted passage means at opposite end regions of each said tube whereby gases under pressure evolved within the tubes can escape into contact with said granular dielectric material surrounding the tube.

6. A current-limiting device comprising a pair of electrically conducting terminal members, each said terminal member having a face disposed in spaced general parallelism with a similar face of the other terminal member, each said face having a multiplicity of cavities therein, a multiplicity of insulating tubes disposed in spaced general parallelism between said faces of the terminal members, a metallic end cap on each end of each of said tubes, one end cap of each of said tubes being seated in one of said cavities in the face of one terminal member and the opposite end cap of each of said tubes being seated in one of said cavities in the face of the other terminal member, an electrically conducting fusible element within each of said tubes connected to the opposite end caps thereof, arc quenching filler material surrounding the fusible element within each of said tubes, and insulating means rigidly connecting said terminal members together.

7. A current-limiting device comprising a pair of electrically conducting terminal members, each said terminal member having a face disposed in spaced general parallelism with a similar face of the other terminal member, each said face having a multiplicity of cavities therein, a multiplicity of insulating tubes disposed in spaced general parallelism between said faces of the terminal members, a metallic end cap on each end of each of said tubes, one end cap of each of said tubes being seated in one of said cavities in the face of one terminal member and the opposite end cap of each of said tubes being seated in one of said cavities in the face of the other terminal member, an electrically conducting fusible element in each of said tubes connected to the opposite end caps thereof, filler material surrounding the fusible element within each of said tubes, insulating walls rigidly connecting said terminal members together, said insulating walls and terminal members defining an enclosure around said multiplicity of tubes, and porous dielectric filler material surrounding each of the multiplicity of tubes within the said enclosure.

8. A current-limiting device comprising a plurality of insulating tubes, an electrically conducting fusible strip extending within each tube, each strip having a plurality of portions of reduced cross-section spaced substantially equidistantly along substantially the entire length of said link and a plurality of portions of relatively larger cross-section intermediate said reduced cross-section portions, each said reduced cross-section portion having a sufficiently small cross-sectional area to initiate arcing at instantaneous currents

far below the available short-circuit current of a circuit in which the device is to serve, and each said relatively larger cross-section portion having a length being a multiple of the length of said reduced cross-section portions, arc extinguishing filler material surrounding the strip in each tube, metallic terminal caps on the opposite ends of each tube and connected to the opposite ends of the fusible strip therein, means electrically connecting at least one terminal cap of each tube to a terminal cap of at least one other tube, pulverulent dielectric material closely surrounding each tube throughout its extent between its terminal caps, and means at the capped ends of the tubes providing restricted passages for venting pressure gases from the tubes into said pulverulent dielectric material.

9. A current-limiting device comprising a plurality of insulating tubes, an electrically conducting fusible strip extending within each of said tubes, each strip being composite of materials of different melting temperatures and having the lower melting temperature material constituting a mid-portion of the length of the strip, and each of said strips having a series of holes substantially equally spaced apart along the strip with at least one of the holes in said mid-portion, an arc extinguishing filler surrounding the entire length of the strip in each of said tubes, electrically conducting terminal means at the opposite ends of each of said tubes and connected to the opposite ends of the fusible strip therein, means electrically connecting at least one terminal of each tube to a terminal of at least one other tube, and dielectric material closely surrounding each of said tubes throughout its extent between its terminal means.

10. A current-limiting device comprising a plurality of insulating tubes, an electrically conducting fusible strip extending within each of said tubes, each strip having a series of holes substantially equally spaced apart along the strip providing a plurality of portions of reduced cross-section spaced substantially equidistantly along substantially the entire length of said link and a plurality of portions of relatively larger cross-section intermediate said reduced cross-section portions, each said reduced cross-section portion having a sufficiently small cross-sectional area to initiate arcing at instantaneous currents far below the available short-circuit current of a circuit in which the device is to serve, and each said relatively larger cross-section portion having a length being a multiple of the length of said reduced cross-section portions, a highly heat-absorbent pulverulent arc extinguishing filler surrounding opposite end portions of the strip in each of said tubes, a thermally and electrically insulating pulverulent material surrounding the central portion of the strip in each of said tubes, electrically conducting terminal means on opposite ends of each of said tubes and connected to opposite ends of the fusible strip therein, means electrically connecting at least one terminal of each of said tubes to a terminal of at least one other of said tubes, and dielectric material closely surrounding each of said tubes throughout its extent between its terminal means.

11. A current-limiting fuse comprising a radially outer electrically insulating casing, a radially inner electrical insulating casing arranged in spaced relation within said radially outer casing, electrically conducting terminal elements arranged on opposite ends of said casings, an electrically conducting fuse link within said radially

inner casing interconnecting said terminal elements, each said fuse link having a plurality of portions of reduced cross-section spaced substantially equidistantly along substantially the entire length of said link and a plurality of portions of relatively larger cross-section intermediate said reduced cross-section portions, each said reduced cross-section portion having a sufficiently small cross-sectional area to initiate arcing at instantaneous currents far below the available short-circuit current of a circuit in which the device is to serve, and each said relatively larger cross-section portion having a length being a multiple of the length of said reduced cross-section portions, a first pulverulent electrically insulating filler within said radially inner casing surrounding said fuse link, a second pulverulent electrically insulating filler within the space defined between said radially outer casing and said radially inner casing, and restricted passage means permitting a limited leakage of gases under pressure from said radially inner casing into said radially outer casing to provide for progressive cooling of arc gases under pressure in two consecutive steps.

12. A current-limiting fuse comprising a plurality of electrically insulating casings arranged in parallel spaced relation, a common housing for said casings, said housing having its lateral wall formed of electrically insulating material and arranged in spaced relation with respect to said casings, an electrically conducting fuse link in each of said plurality of casings, each said fuse link having a plurality of portions of reduced cross-section spaced substantially equidistantly along substantially the entire length of said link and a plurality of portions of relatively larger cross-section intermediate said reduced cross-section portions, each said reduced cross-section portion having a sufficiently small cross-sectional area to initiate arcing at instantaneous currents far below the available short-circuit current of a circuit in which the device is to serve, and each said relatively larger cross-section portion having a length being a multiple of the length of said reduced cross-section portions, common electrically conducting terminal elements for the fuse link in each of said plurality of casings arranged on opposite ends of said housing, a pulverulent electrically insulating filler in each of said plurality of casings, a pulverulent electrically insulating filler in the space defined between said plurality of casings and said lateral wall of said housing, and restricted passage means permitting a limited leakage of gases under pressure from said plurality of casings into said housing to provide for progressive cooling of arc products under pressure in two consecutive stages.

13. A current-limiting fuse comprising a radially outer electrically insulating casing, a radially inner electrically insulating casing arranged in spaced relation within said radially outer casing, electrically conducting terminal elements arranged on opposite ends of said casings, an electrically conducting fuse link within said radially inner casing interconnecting said terminal elements, said fuse link having a plurality of portions of reduced cross-section spaced substantially equidistantly along substantially the entire length of said link and a plurality of portions of relatively larger cross-section intermediate said reduced cross-section portions, each said reduced cross-section portion having a sufficiently small cross-sectional area to initiate arcing at instantaneous currents far below the available

short-circuit current of a circuit in which the device is to serve, and each said relatively larger cross-section portion having a length being a multiple of the length of said reduced cross-section portions, a pulverulent electrically insulating gas evolving filler within said radially inner casing surrounding one portion of said fuse link, a pulverulent electrically insulating non gas evolving filler within said radially inner casing surrounding another portion of said fuse link, a pulverulent electrically insulating non gas evolving filler within the space defined between said radially outer casing and said radially inner casing, and a restricted passage means between said radially inner casing and said space to permit a limited flow of gas evolved from said gas evolving filler through said non gas evolving filler within said radially inner casing into said non gas evolving filler within said space.

14. A current-limiting fuse comprising a radially outer electrically insulating casing, a radially inner electrically insulating casing arranged in spaced relation within said radially outer casing, electrically conducting terminal elements arranged on opposite ends of said casings, an electrically conducting fuse link within said radially inner casing interconnecting said terminal elements, a pulverulent electrically insulating gas evolving filler within said radially inner casing surrounding the axially inner portion of said fuse link, quartz sand fillers within said radially inner casing surrounding the axially outer portions of said fuse link, a pulverulent electrically insulating non gas evolving filler within the space defined between said radially outer casing and said radially inner casing, and restricted passage means on both ends of said radially inner casing to permit limited flows of gas evolved from said gas evolving filler in opposite directions through said quartz sand fillers into said non gas evolving filler.

15. A current-limiting fuse comprising a radially outer electrically insulating casing, a radially inner electrically insulating casing arranged in spaced relation within said radially outer casing, a pair of electrically conducting terminal blocks arranged on opposite ends of said radially outer casing and defining recesses for receiving opposite ends of said radially inner casing, an electrically conducting fuse link within said radially inner casing, a first pulverulent arc-extinguishing filler surrounding said fuse link, a second pulverulent electrically insulating filler within the space defined between said radially outer casing and said radially inner casing, and a pair of electrically conducting terminal caps on opposite ends of said radially inner casing electrically connected to the opposite ends of said fuse link and arranged within said recesses defined by said terminal blocks, said terminal caps and said radially inner casing being adapted to define upon a predetermined increase in pressure within said radially inner casing a restricted circular gap permitting a limited escape of gas under pressure from said radially inner casing into said radially outer casing, said terminal caps extending beyond said recess to cause direct discharge of gas escaping from said casing into said second pulverulent filler.

16. A current-limiting fuse comprising a plurality of electrically insulating casings arranged in parallel relation, a common electrically insulating housing for said casings, electrically conducting terminal blocks arranged on opposite ends of said housing and defining recesses for re-

ceiving the axially outer ends of said plurality of casings, an electrically conducting fuse link in each of said plurality of casings, a filler of quartz sand in each of said plurality of casings surrounding said fuse link, a pulverulent electrically insulating filler having a relatively high heat absorbing capacity arranged in the space defined between said plurality of casings and the lateral wall of said housing, and a pair of electrically conducting terminal caps on the axially outer ends of each said casing electrically connected to the opposite ends of said fuse link therein and arranged within said recesses defined by said terminal blocks, said terminal caps and said casings being adapted to define upon a predetermined increase in pressure within said casings restricted circular gaps permitting a limited escape of gas under pressure from said casings into said housing, said terminal caps extending beyond said recesses to cause direct discharge of gas escaping from said casings into said second pulverulent filler.

17. A current-limiting fuse comprising a radially outer electrically insulating casing, a radially inner electrically insulating casing arranged in spaced relation within said radially outer casing, relatively massive metallic terminal elements arranged on opposite ends of said casings in intimate heat-receiving relation to the opposite ends of said radially inner casing, an electrically conducting fuse link within said radially inner casing interconnecting said terminal elements, each said terminal element having relatively large heat-absorbing capacity for large and rapid absorption and extraction of heat from said radially inner casing in response to substantially generation of heat within said radially inner casing, a first pulverulent electrically insulating filler within said radially inner casing surrounding said fuse link, and a second pulverulent electrically insulating filler within the space defined between said radially outer casing and said radially inner casing.

18. A current-limiting fuse comprising a plurality of electrically insulating casings arranged in parallel spaced relation, a common electrically insulating housing for said casings with its lateral wall arranged in spaced relation with respect to said casings, an electrically conductive fuse link in each of said plurality of casings, relatively massive metallic terminal elements secured to the opposite ends of said common housing and maintained thereby in electrical connection with the opposite ends of all of said fuse links, said terminal elements connecting said fuse links in parallel, and each terminal element having relatively large heat-absorbing capacity for large and rapid absorption and extraction of heat from said casings in response to substantial generation of heat within said casings, pulverulent electrically insulating filler material within said casings surrounding said fuse links, and pulverulent electrically insulating filler material within the space defined between said common housing and said casings.

19. A current-limiting fuse comprising a plurality of electrically insulating casings arranged in parallel relation, a common electrically insulating housing for said casings, relatively massive metallic terminal elements arranged on opposite ends of said housing and defining recesses for receiving the opposite ends of said casings, an electrically conducting fuse link in each of said casings, pulverulent electrically insulating filler material in each of said casings surround-

ing the fuse link therein, a pulverulent electrically insulating filler material in the space defined between said casings and said common housing, and a pair of electrically conducting terminal caps on the opposite ends of each of said casings and arranged within said recesses defined by said terminal elements, each said terminal element having relatively large heat-absorbing capacity for large and rapid absorption and extraction of heat from said casings in response to substantial generation of heat within said casings.

20. A current-limiting device comprising a pair of relatively massive metallic terminal members, each said terminal member having a face disposed in spaced general parallelism with a similar face of the other terminal member, each said face having a plurality of cavities therein, a plurality of electrically insulating tubes disposed in spaced general parallelism between said faces of the terminal members, a metallic end cap on each end of each of said tubes, one end cap of each of said tubes being seated in one of said cavities in the face of one terminal member and the opposite end cap of each of said tubes being seated in one of said cavities in the face of the other terminal member, an electrically conducting fusible element within each of said tubes connected to the opposite end caps thereof, and electrically insulating filler material surrounding the fusible element within each of said tubes, said terminal members having relatively large heat-absorbing capacity for large and rapid absorption and dissipation of heat from said tubes and end caps in response to substantial generation of heat within said tubes.

21. A composite current-limiting fuse formed by an assembly of a plurality of identical separate fuse units adapted to be arranged in parallel in an electric circuit, each said fuse units comprising an electrically insulating casing member, electrically conducting terminal elements on opposite ends thereof, an electrically conducting fuse link having a plurality of portions of restricted cross-sectional area within said casing member and electrically connected to the opposite terminal elements thereof, and a pulverulent arc-extinguishing filler surrounding said link, said fuse units being arranged in spaced relation to form a pattern of concentric shells to cause the total current through said fuse units to be unequally distributed among fuse units pertaining to different shells to cause fusion of the portions of restricted cross-sectional area of links of fuse units pertaining to different shells to occur at slightly different points of time.

22. A composite current-limiting fuse formed by an assembly of a plurality of identical separate fuse units adapted to be arranged in parallel in an electric circuit, each said units consisting of a separate electrically insulating tubular casing member having separate electrically conducting terminal elements on opposite ends thereof and an electrically conducting fuse link electrically connected to said separate terminal elements and a pulverulent arc-extinguishing filler therein, said fuse units being arranged in spaced relation to form a pattern of concentric shells, and a pulverulent electrically insulating substance provided in the spaces formed between said fuse units tending to maintain said fuse units in their shell-pattern position.

23. A current-limiting low-voltage fuse comprising a tubular casing of insulating material, a ribbon-type fuse link within said casing, a

pulverulent arc-extinguishing filler within said casing surrounding said link, and terminal caps supported by said casing and conductively connected to said link, said caps having cylindrical lateral portions engaging the axially outer ends of said casing under sufficiently high pressure to normally provide gas-tight seals for said casing, and said cylindrical portions of said caps engaging said axially outer ends of said casing under sufficiently low pressure to permit egress of gaseous products therefrom on the occurrence of excess pressures therein through leakage paths then forming between said cylindrical portions of said caps and said axially outer ends of said casing.

24. A current-limiting low-voltage fuse comprising a casing of insulating material, a ribbon-type fuse link within said casing, said link having a plurality of portions of greatly reduced width and intermediate portions of much larger width, the length of said reduced width portions being small in comparison to the length of said larger width portions, a pulverulent arc-extinguishing filler within said casing surrounding said link, and terminal caps mounted on the axially outer ends of said casing and conductively connected to said link, said caps being so loosely mounted on said casing as to permit egress of gaseous products therefrom on the occurrence of excess pressures therein through leakage paths then forming between said casing and said caps. 30

25. A current-limiting low-voltage fuse comprising a casing of insulating material, a ribbon-type fuse link within said casing, said link having a plurality of portions of greatly reduced

5 width and intermediate portions of much larger width, said reduced width portions being short in comparison to said larger width portions and arranged substantially along the entire length of said link, a pulverulent arc-extinguishing filler within said casing surrounding said link, and terminal caps supported by said casing and conductively connected to said link, said caps having cylindrical lateral portions engaging the axially outer ends of said casing under sufficiently high pressure to normally provide gas-tight seals for said casing, and said cylindrical portions of said caps engaging said axially outer ends of said casing under sufficiently low pressure to permit egress of gaseous products therefrom on the occurrence of excess pressures therein through leakage paths then forming between said cylindrical portions of said caps and said axially outer ends of said casing.

WILLIAM S. EDSALL.
KENNETH W. SWAIN.
